UNITED STATES PATENT OFFICE.

EDWARD WILLIAM LLOYD AND CHARLES WESLEY HUTCHINSON, OF NEW-CASTLE-UPON-TYNE, ENGLAND, ASSIGNORS TO SIR W. G. ARMSTRONG, MITCHELL & CO., LIMITED, OF SAME PLACE.

APPARATUS FOR LAUNCHING TORPEDOES.

SPECIFICATION forming part of Letters Patent No. 548,374, dated October 22, 1895.

Application filed May 3, 1895. Serial No. 548,023. (No model.)

To all whom it may concern:

Be it known that we, EDWARD WILLIAM LLOYD, formerly a commander in the British Navy, and now of the firm of Sir W. G. Armstrong, Mitchell & Co., Limited, and CHARLES WESLEY HUTCHINSON, engineer, both residing at Elswick Works, Newcastle-upon-Tyne, England, subjects of the Queen of Great Britain, have invented certain new and useful Improvements in Apparatus for the Launching of Locomotive-Torpedoes under Water, of which the following is a specification.

This invention relates more especially to apparatus for launching locomotive-torpedoes from the broadside of a ship by an impulse imparted by compressed gas.

The gas is obtained preferably by burning an explosive, such as cordite, in a closed combustion-chamber.

The apparatus consists of a fixed outer tube or casing closed by a door in rear and fitted in front with a sluice-valve which when the apparatus is not in use (and at other times when required) serves to exclude the sea. The outer tube or casing contains another tube which receives the torpedo within it, the same being admitted by a door at the rear end of the inner tube. This inner tube we term the "torpedo-guide."

Between the two tubes at their rear ends an annular space is provided, terminating in front at a gland formed in the outer tube about midway of its length. The torpedo-guide can travel longitudinally through this gland. Compressed gas from the combustion-chamber enters the annular space between the tubes and drives the torpedo-guide containing the torpedo forward until it is arrested by a hydraulic buffer-stop. So the torpedo-guide is made to protrude from the casing. There is a valve upon the rear door of the torpedo-guide by which the compressed gas may pass also into the interior of the torpedo-guide, and the gas so admitted into the torpedo-guide impinges upon the torpedo, drives it forward, and launches it upon its course.

There are grooves within the torpedo-guide two or more from end to end of it at the top and two or more at the bottom, and entering

the grooves there are corresponding ribs upon the torpedo extending a short distance along it where it is of its greatest diameter.

The fore part of the torpedo-guide, which in the launching operation is protruded from the ship's side, is cut away on one side and so is somewhat of a trough-like form. Hence as soon as the ribs upon the torpedo clear the guiding-grooves the torpedo is free and can escape more or less laterally.

The gaseous pressure is generated in a chamber preferably at the side of the casing and communicating with the annular space within.

To moderate the rush of gas resulting when the charge of cordite or other explosive is ignited, the gas is checked and baffled by being made to pass through perforations in a plate and to flow in a circuitous course. The annular space within the casing serves as an expansion-chamber for the gases, and the gases when in this chamber exert a pressure in rear of the torpedo-guide and drive it forward, as already explained. The valve for admitting the gas to the interior of the torpedo-guide is controlled by a cam-surface, a spring, and a lever, so that the pressure applied within and without the torpedo-guide may be duly proportioned.

When the apparatus is used upon a ship in rapid motion, the lateral pressure of the water upon the fore part of the torpedo-guide when protruded is very great. In order that the torpedo-guide may work freely under this strain, we provide rollers upon the casing to support it. We also provide a rack and pinion or other gear to withdraw the torpedo guide if in any case it should fail to return automatically.

In order that our invention may be fully understood, we will proceed to describe the drawings annexed.

Figure 1 is a longitudinal and horizontal section of launching apparatus arranged in accordance with our invention. Figs. 2 and 3 are transverse sections of the same, the one near the fore end and the other near the after end. Figs. 4 and 5 show details on a larger scale. Fig. 4 is a longitudinal section and Fig. 5 is a transverse section.

a is the outer tube or casing. *b* is a sluice-valve at its fore end, and *c* is a portion of the ship's side to which the sluice-valve is fixed.

d is a door which closes the after end of the tube or casing *a*. This door is opened for the admission of the torpedo and is closed and locked gas-tight behind it.

e is the inner tube or torpedo-guide. For half of its length it is cylindrical and it is held in a gland formed in the casing at *f*. Hand-gear, as seen at *g*, is provided to adjust the tightness of the gland.

e' e' are guiding-grooves passing from end to end of the torpedo-guide.

h is the torpedo. It is seen in its place within the torpedo-guide. *h' h'* are ribs on the torpedo entering the guiding-grooves *e'*.

It will be observed that both at the top and bottom of the torpedo-guide a pair of grooves *e* is provided and the torpedo has corresponding ribs. This duplication of the grooves and ribs is found to be necessary to obtain sufficient strength to withstand the strain in launching.

i is the door at the rear end of the torpedo-guide. It opens to admit the torpedo and closes water-tight behind it. The door is provided with a suitable fastening.

k is a valve of large area mounted on the door *i*. A pair of springs tend to hold the valve to its seat. The principal spring *k'* abuts upon a lever *l* at one end and upon a disk on the stem of the valve at the other end.

m is a cam-like bar on which the lever *l* bears. It is fixed within the casing *a*.

The lever *l* when the torpedo-guide travels forward within the casing moves, as it may be controlled by the inclines upon the bar *m*, and so the compression of the spring *k'* is made to vary and the valve is allowed to open more or less freely.

e² is the fore part of the torpedo-guide, which is protruded from the ship's side in launching the torpedo. This part of the guide is open on the side facing the stern of the ship to allow the torpedo to escape laterally.

e³ e⁴ are holes formed in the fore part of the torpedo-guide. They serve for the water to stream through, so that the water passing the ship may have access to the hinder end of the torpedo before it gets free of the guide.

n n are rollers on the casing to support the torpedo-guide when protruded. They allow it to move freely under the heavy cross-strain to which it may be exposed.

o is a lug upon the after end of the torpedo-guide. It serves to keep the torpedo-guide central in the casing.

p is a cavity formed around the torpedo-guide, and *q* is a corresponding annular rib or thickening at the fore end of the casing. When the torpedo-guide arrives at the fore end of its course, the rib *q* is received into the cavity *p* and water is trapped and can only escape by the narrow clearance-spaces. Thus the torpedo-guide is brought to rest without undue shock to the mechanism.

r are rack-teeth formed in the side of the torpedo-guide, and *s* is a pinion gearing with the teeth. Power can be applied to turn this pinion to withdraw the torpedo-tube in case it should fail to return automatically.

t is the combustion-chamber. In it there is a socket *t'* to receive a central-fire cordite-cartridge. The chamber is closed behind the cartridge by a cover. (Not shown.) The socket carries a bell-like baffle *u*. It is formed of a piece with the socket *t'* and its stem is slit longitudinally.

When the cartridge is fired, the gases issue by the slits and then are turned back by the bell-like baffle. They reach the exit from the chamber, and this is guarded by the perforated plate *v*. It further delays the exit of the gases.

The apparatus is used in the following way: The sluice-valve *b* being closed, the water is run out of the apparatus by opening a drain-cock which is fitted upon the fore part of the casing *a*. The rear doors *d* and *i* are now opened. The torpedo is put into the torpedo-guide and the doors are closed and secured behind it. The sluice-valve *b* is then opened. It admits the sea-water to the interior of the torpedo-guide around the torpedo. Finally a cartridge is placed and made ready for firing in the socket *t'* of the combustion-chamber. On firing, the gases pass from the combustion-chamber into the annular space between the casing and the torpedo-guide. It here expands, and exerting a pressure on the rear of the torpedo-guide it drives it forward. If the gas be of sufficient pressure, and it is intended that it should be, the valve *k* opens partially and admits some of the gas into the interior of the torpedo-guide. The gas so admitted commences to drive the water out from behind the torpedo and to start the torpedo itself into movement along the guide. When the torpedo-guide reaches the fore end of its course, it is stopped by the hydraulic buffer-stop, as already described; but previous to this the valve *k* is allowed to open more freely by the operation of the lever *l* and the cam-like bar *m*. By the rush of gas which then takes place through the torpedo-guide the torpedo is driven out with high velocity. When the gases have escaped, the sea will return to the interior of the torpedo-guide and the water-pressure will drive it rapidly back to its original position. If it should stick, it is brought back by the rack and pinion, as already explained. The sluice cock *b* may now again be closed.

Residual gases may be permitted to escape by opening a valve upon the flue-pipe *w*; or the flue-pipe valve may be arranged to open automatically.

Compressed air or gas from other sources may be used in place of that derived from the combustion of an explosive or rapidly-burning material.

Figs. 4 and 5 show details of the gear for tightening the gland *f*. The hand-wheel *g* has

upon its axis a worm g' , which engages a pinion g^2 , and on the axis of this pinion there is a spur-wheel g^3 . The gland-ring f' has a screw-thread upon it and it screws into its place, so that it is only necessary to turn the ring f' in order to compress the packing at f to the extent necessary to make a tight joint. The ring f' has teeth on its exterior engaging those of the spur-wheel g^3 . Hence by the gear-train described the hand-wheel g gives control of the gland.

What we claim is—

1. Torpedo launching apparatus comprising an outer tube or casing, an inner tube receiving the torpedo within it and serving as a torpedo guide, a gland in the casing through which the torpedo guide can slide, means for admitting compressed fluid to the space between the two tubes in rear of the gland and also into the inner tube or torpedo guide in rear of the torpedo.

2. Torpedo launching apparatus comprising an outer tube or casing, an inner tube or torpedo guide, means for admitting compressed fluid to a confined space between them, and a loaded valve upon the torpedo guide allowing some of the compressed fluid to enter into the torpedo guide behind the torpedo when its pressure is sufficient to lift the valve.

3. Torpedo launching apparatus comprising an outer tube or casing, an inner tube or torpedo guide, means for admitting compressed fluid to a confined space between them, a valve upon the torpedo guide allowing some of the fluid to enter the torpedo guide behind the torpedo and an inclined cam

like surface controlling the opening of the valve.

4. Torpedo launching apparatus comprising an outer tube or casing, an inner tube or torpedo guide, a gland in the casing through which the torpedo guide can slide, means for admitting compressed fluid to the confined space between the casing and the torpedo guide, and gearing on the exterior of the casing for regulating the tightness of the gland.

5. Torpedo launching apparatus comprising an outer tube or casing, an inner tube or torpedo guide, means for protruding the torpedo guide from the casing, rollers arranged in chambers upon the casing and bearing against the guide enabling the torpedo guide to move freely when protruded and means for ejecting the torpedo from the inner tube or torpedo guide.

6. Torpedo launching apparatus comprising an outer tube or casing, an inner tube or torpedo guide, means for protruding the torpedo guide from the casing, and a cavity in which water is confined by the torpedo guide as it comes to the outer end of its course whereby the movement of the torpedo guide is checked.

7. In torpedo launching apparatus, a gas generating appliance consisting of the combination of the chamber t containing a cartridge socket t' , with lateral slits, and a bell-like baffle u , surrounding the socket.
